CLAIM

The ornamental design for a folding beach umbrella as shown and described.

DESCRIPTION

FIG. 1 is a front, right and top perspective view of a folding beach umbrella, showing our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a partial enlarged view of an area labeled 8 in FIG. 1.

FIG. 9 is a partial enlarged view of an area labeled 9 in FIG. 1.

FIG. 10 is a partial enlarged view of an area labeled 10 in FIG. 1.

FIG. 11 is a partial enlarged view of an area labeled 11 in FIG. 1; and,

FIG. 12 is a partial enlarged view of an area labeled 12 in FIG. 1.

The dot-dash broken lines in FIGS. 1, 8, 9, 10, 11 and 12 depict the boundaries of the enlargements that form no part of the claimed design.
